NEEDLE PROTECTOR FOR DETECTING DEFECTIVE NEEDLE OPERATION ON A KNITTING MACHINE

Robert W. Clemens, Malverne, N.Y., assignor to Wesco Industries Corporation, Plainview, N.Y.

Filed Apr. 12, 1974, Sr. No. 460,474

Term of patent 14 years

Int. Cl. D15—06

U.S. Cl. D92—15

FIG. 1.

FIG. 2.

FIG. 3.

FIG. 4.

FIG. 5.

FIG. 6.

FIG. 7.

FIG. 1 is a perspective view of a needle protector for detecting defective needle operation on a knitting machine showing my new design;

FIG. 2 is a front elevational view thereof;

FIG. 3 is a top plan view thereof;

FIG. 4 is an inverted rear elevational view thereof;

FIG. 5 is a bottom plan view thereof;

FIG. 6 is a right side view thereof; and

FIG. 7 is a left side view thereof.

I claim:

The ornamental design for a needle protector for detecting defective needle operation on a knitting machine, substantially as shown.
